His Attorney.

UNITED STATES PATENT OFFICE

LAWRENCE H. JUNKEN, OF HADDONFIELD, NEW JERSEY, ASSIGNOR TO GENERAL ELECTRIC COMPANY, A CORPORATION OF NEW YORK

ELECTRICAL REGULATING SYSTEM

Application filed April 18, 1930. Serial No. 445,435.

My invention relates to electrical regulators and regulating systems and particularly to voltage regulators which are associated with polyphase systems.

5 Electrical regulators when associated with a polyphase system were originally connected to the system in such a manner that they were responsive only to variations in the regulated condition occurring in one of the phases.

10 So long as the system was balanced this proved perfectly satisfactory but when the system became unbalanced, as through the occurrence of a single phase short circuit, the regulator might or might not respond in 60 the proper manner depending upon how the particular phase to which the regulator was connected might be affected by the unbalanced condition.

15 It is well known that a single phase short 65 circuit on a polyphase machine, such as a three phase alternator, will tend to produce conditions of instability. Formerly this was not especially serious but in recent years, due to the trend toward longer transmission lines 70 and increasing interconnections between systems or for economic reasons, synchronous systems are being operated closer to their limits of steady state stability with the result that the marginal increase in load which 75 30 may be added to a system without causing the machines to break out of synchronism has been steadily decreasing.

The fact that voltage regulators associated with synchronous machines operate to 80 increase the breakdown torque of these machines, through their action in increasing the excitation and hence the electromagnetic bond between the rotor and stator of the machines, in their effort to maintain constant 85 35 voltage is also well known. Thus from the point of view of system stability and transient conditions under short circuits it is important that the voltage regulators should respond not only to variations in the voltage 90 of balanced systems, but they should also act 40 to increase the excitation of their associated machines as a result of unbalanced voltage 95 conditions.

This problem may be attacked in either of 50 two ways; namely, one, by devising a special

polyphase device which may be connected directly to the polyphase line for actuating the regulator in the proper manner in response to both balanced voltage variations and single phase variations or, two, by inserting between the ordinary actuating means of the regulator and the polyphase circuit an intermediate network which applies to the ordinary regulator actuating means a voltage which varies in proportion to balanced variations and which also varies in the proper manner in response to unbalanced conditions of the circuit. My invention relates to the latter way and in accordance therewith I provide means for 60 impressing on the ordinary operating means of a regulator a voltage which is the arithmetical sum of a plurality of in phase harmonic voltages which are individually proportional, but not necessarily directly proportional, to the different phase voltages of the system.

An object of my invention is to provide a new and improved regulator and regulating system which will produce a proper regulating action, when operated in conjunction with a polyphase circuit and polyphase dynamo electric machine, in response to variations in both the balanced polyphase electrical condition being regulated and single 80 phase variations of said condition.

Another object of my invention is to provide new and improved means which when associated with a translating device such as the ordinary operating means of a conventional electrical regulator will cause it to respond properly to both balanced and unbalanced variations in a condition of a polyphase circuit.

A further object of my invention is to provide a new and improved highly sensitive electrical regulator on which the effect of variations in the electrical condition being regulated varies at a greater rate than does the regulated condition itself.

My invention will be better understood from the following description taken in connection with the accompanying drawings and its scope will be pointed out in the appended claims.

In the drawings, Fig. 1 is a diagrammatic showing of an embodiment of my invention. Fig. 2 is a set of comparison curves for illustrating the increased sensitivity of my regulator and Fig. 3 illustrates another embodiment of my invention.

Referring now to Fig. 1 of the drawings in which I have shown as the polyphase dynamo electric machine to be regulated an alternator 1, although as the description of my invention proceeds it will become obvious to those skilled in the art that my invention is equally applicable to the regulation of other polyphase dynamo electric machines, such as synchronous motors or synchronous condensers. Alternator 1 has an armature 2 which is connected through brushes 3 to a load circuit 4 on which, for purposes of illustration, it will be assumed that it is desired to hold constant voltage. The field winding 5 of the regulated machine is energized by the usual shunt wound exciter 6 which has an armature 7 and a field winding 8. For varying the excitation of the exciter and hence of the regulated machine a resistance 9 is connected in the field circuit of the exciter 6 and is arranged to be controlled by the action of the regulator 10.

Regulator 10 has been shown as of the conventional vibratory contact Tirrill type, but any regulator which has a main control element such as an electromagnet or contact making voltmeter is suitable for use with my invention. This regulator includes the usual vibratory contacts comprising contact 11 whose movement is governed by the anti-hunting coil 12 through the usual system of levers 13. Anti-hunting coil 12 is connected across the exciter 6 and its pull is balanced by the usual system of springs which are represented by spring 14. The other contact is contact 15 whose movement is governed by main control 16 through the usual system of levers 17. Dashpot 18 serves to dampen the motion of this contact.

The usual practice, as already referred to, is to connect coil 16 directly across one of the phases of circuit 4 when it is desired to regulate voltage. However, as previously pointed out the regulator is then responsive to only one of the voltages of the circuit with the result that the regulator may fail to increase the excitation of the regulated machine when a severe unbalanced single phase load is thrown on it.

In order to make coil 16 responsive to single phase voltage variations, as well as to balanced polyphase voltage variations of circuit 4 I provide a network 19 which in the embodiment of my invention illustrated comprises essentially a polyphase iron core transformer having a primary winding 20 and a secondary winding 21 which is open mesh connected, or, as circuit 4 is a three phase circuit, more specifically open delta connected. It is immaterial to my invention in its broad-

est aspects whether primary winding 20 is mesh connected or star connected, but it is important that the transformer be so designed that its magnetizing current at least partially saturates its core. It will of course be obvious to those skilled in the art that three single phase transformers could be connected so as to form the equivalent of the three phase transformer shown without departing from my invention in its broader aspects. Operating coil 16 is connected across the open terminals of secondary winding 21. A condenser 22, which may or may not be adjustable as desired is connected in the circuit of core 16 and an adjustable resistance 23 is connected across the condenser 22 for reasons to be explained hereinafter.

In describing the operation of my invention I will first describe the operation of network 19. Assume that alternator 1 is operating in a normal manner to impress a balanced three phase voltage on circuit 4 and that this circuit is supplying a balanced load. Under these circumstances each of the phase windings of the secondary winding 21 will have induced in it a voltage which is numerically equal to the voltage induced in each of the other phase windings but which makes a phase angle of 120 degrees with each of the other voltages. However, as the core of the transformer becomes magnetically saturated during at least the peaks of the cycle of the impressed voltage the flux wave will be flat topped even if the impressed voltage is sinusoidal. This is because as the core becomes saturated its permeability decreases so that the rate of change of flux per unit change in instantaneous impressed voltage becomes less, which is merely another way of saying that the slope of the flux wave becomes flatter at the top. As the voltage induced in each secondary phase winding is produced by the rate of change of flux in the core this voltage will also be flat topped.

It is well known that a flat topped voltage wave contains a marked third harmonic. Each of the phase voltages of the secondary winding 21 may therefore be considered as comprising two component sinusoidal voltages of fundamental and triple or third harmonic frequency respectively. As the fundamental frequency components in each phase winding are in phase with their respective resultant phase voltages it is clear that their vector sum around the delta is zero for it is fundamental in vector notation that the vector sum of any number of vectors making a closed loop is zero. The triple frequency or third harmonic components in each phase winding are, however, all in phase so that their vector sum around the loop of the delta is equal to their arithmetic sum. That the third harmonic voltages are in phase with each other in a three phase system is obvious for if the three fundamen-

tal sine waves and the third harmonic sine wave are visualized it will be seen that the third harmonic wave is symmetrical with respect to each of the three fundamental waves. It thus follows that there is a triple frequency voltage, which when the system is balanced is made up of three equal in phase components, tending to produce a circulating current in the delta and which appears across the opening in the delta.

As there is no real load connected to transformer 19 the current that it takes must all be magnetizing or exciting current. With the mesh or delta connection of the primary 15 winding 20, as shown in Fig. 1, there is provided a closed circuit for the third harmonic component of the magnetizing current. The third harmonic voltages appearing in the phase windings of secondary 21 will therefore be functions of the third harmonic voltages in the phase windings of primary 20 and consequently the greater these latter voltages are the greater the former voltages will be. For this reason, the greater the impedance of the primary winding the greater the third harmonic voltage will be. With the primary winding star or Y connected, as in Fig. 3, there can ordinarily be no third harmonic current flow therein because the 30 third harmonic phase voltages add up to zero in the line voltages and consequently no third harmonic current will flow in line 4. As will be explained later, this is not the case if the system is a grounded neutral one. Consequently, the third harmonic component of the exciting current of the transformer must of necessity all flow in the secondary winding 21. Variations in primary winding impedance therefore have no effect on 40 the star connected primary winding connection.

Doubtless the resultant voltage induced in each of the secondary phase windings contains other harmonic components than the 45 third, for it is unlikely that the flattopped flux wave produced by saturation of the core will be completely satisfied by a Fourier's series extending only to the triple frequency terms. There can of course be no even numbered 50 harmonics if the positive and negative portions of the line voltage wave are symmetrical, which is the case with most alternators. The next possible harmonic would therefore be the fifth but due to the fact that its magnitude is relatively small compared with the 55 third and also to the fact that it is not in phase in each of the secondary phase windings so that it tends to cancel itself around the delta loop its effect, and consequently, the 60 effect of any higher odd harmonics, is negligible. This is especially true if the delta loop has part of its third harmonic inductive 65 reactance neutralized by a condenser for then the impedance of the loop to other harmonics will be higher than normal.

It should be noted, however, that although the fifth harmonic is unimportant in the three phase system illustrated it is the harmonic which would be most prominent across the opening of an open mesh connected secondary winding of a five phase transformer connected to a five phase circuit. It will thus be evident to those skilled in the art that my invention is not limited to three phase systems in which the third harmonic is employed and that by the use of proper connections it is applicable to other polyphase systems in which other harmonics are employed.

It is not essential to my invention, in its broadest aspects, that the transformer core should become magnetically saturated in the usual sense of the term. This is for two reasons. The first is that the magnetization curve of practically all core materials is not an absolutely straight line below the knee of the curve. It is always tending to become flatter but at the knee this is greatly accentuated. This is proved by the fact that practically all transformers have more or less of a third harmonic component in their magnetizing currents. Thus, while saturation improves the operation of my invention, by accentuating the production of third harmonics, it is not absolutely essential. The 90 second reason is that in certain cases my invention will operate on third harmonic voltages in the main circuit 4 without the necessity of producing third harmonics by saturation. Thus, suppose circuit 4 contains 95 third harmonics in its line voltages, produced for example by saturation in a generator with a high impedance mesh connected winding, and that transformer 19 is connected as in Fig. 1. Under these conditions, the regulator will respond to single phase and balanced voltage variations of line 4. Likewise, if the generator is star connected with its neutral grounded and if its phase winding voltages contain third harmonics and if the 100 primary winding 20 is star connected with its neutral grounded the same action will take place regardless of whether the transformer core saturates or not. This is because the ground will act as a return conductor of the third harmonic currents.

As the magnitude of each third harmonic voltage is proportional to the magnitude of its actual phase voltage it follows that for balanced conditions the third harmonic voltage across the opening in the delta varies in proportion to variations in line voltage. For balanced conditions therefore the third harmonic voltage is an index of the line voltage and it may therefore be applied to the operating means of any regulator.

For unbalanced conditions, such as a single phase short circuit, the voltage of one phase, and consequently the magnitude of the third harmonic which is proportional to 130

it will drop with the result that the total third harmonic voltage across the opening in the delta will decrease as the voltage is equal to the arithmetical sum of all the third harmonic voltages. This third harmonic voltage, if applied to a regulator will therefore act in the proper manner to increase the excitation of a regulated machine in response to single phase voltage variations on the circuit as well as to cause the regulator to act properly in response to balanced voltage variations.

An important consequence of the use of a saturating transformer is that the rate of change of third harmonic voltage in the open delta is greater than the rate of change of voltage on line 4 with the result that any regulator or regulating system employing this voltage has an increased sensitivity. This may readily be seen by referring to Fig. 2, in which curve 1 shows how the current in main control coil 16 varies with variations in phase voltage when the coil is connected directly across one of the phases of circuit 4 while curve 2 shows the same relation of coil current and phase voltage when coil 16 is connected across the opening in secondary winding 21. At one hundred percent phase voltage curve 2 is considerably steeper than curve 1 thus showing that for equal changes in phase voltage the changes in coil current are much greater when apparatus embodying the principle of my invention is used than when the regulator is connected in the ordinary manner. Curve 1 is a straight line through the origin of the coordinate axes, which of course is as it should be, as it is merely a graphical representation of the single order equation symbolizing ohms law. Curve 2 resembles in shape the magnetization curve of iron with the coordinates reversed. This also is as it should be theoretically, for the third harmonic voltage, which is a measure of the coil current, varies with the saturation of the transformer core which, of course, varies with variations in the magnitude of the peaks of the phase voltage.

It is interesting to note that the slope of curve 2 becomes flatter towards the top. This is thought to be because as the phase voltage increases the knee of the saturation curve is really passed at the beginning of the voltage wave instead of at the peaks only so that the flux wave becomes less flat topped with the result that the third harmonic voltage decreases.

Although the voltage across the opening of the open delta connected secondary winding 21 may be made to operate a regulator satisfactorily when directly connected thereto, an improved operation is secured through the adjustment of condenser 22 and resistance 23 so as to partially neutralize the third harmonic inductive reactance of the operating coil circuit. This has the double ad-

vantage of making the impedance of the circuit low with respect to the third harmonic current and high with respect to a current of fundamental frequency which might tend to flow in the circuit under unbalanced conditions.

Keeping in mind that coil 16 is energized by a voltage which varies in proportion, but not in direct proportion, to variations in the balanced voltage of circuit 4 and which decreases when the voltage of one or more of the phases of circuit 4 decreases I will now describe the operation of my regulating system as a whole. First, however, it should be noted that although I have shown and described an arrangement by which coil 16 is responsive to voltage conditions of circuit 4 my invention is not so limited and that it cannot but occur to those skilled in the art that primary winding 20 might be connected to circuit 4 in many other ways so as to be responsive to other electrical conditions of that circuit, such as current, through the use of a suitable polyphase current transformer, without departing from my invention in its broader aspects.

Returning now to the operation of my system as a whole and assuming that conditions in circuit 4 are stable it will be seen that anti-hunting contact 11 is vibrating rapidly for the following reasons. When contacts 11 and 15 are in engagement part of resistance 9 is short-circuited thereby increasing the field current of exciter 6 and raising its terminal voltage. This in turn causes the pull of coil 12 to increase with the result that lever system 13 causes contact 11 to become disengaged from contact 15. This reinserts the resistance 9 in the shunt circuit of field winding 8 with the result that the exciter voltage falls, causing the pull of magnet 12 to decrease so that contacts 11 and 15 reengage. This action, as is well known, is very rapid and does not produce appreciable pulsations in the current of the alternator field 5. If now the energization of main control coil 16 varies, in response to variations in voltage on circuit 4, contact 15 will be moved up or down by the lever system 17. Thus if the energization of magnet 16 decreases as a result of either a balanced or a single phase fall in voltage of circuit 4 contact 15 will rise, thereby reducing the ratio of time open to time closed of contacts 11 and 15 and increasing the average exciter voltage and hence the average excitation of machine 1. Likewise, if contact 15 descends this ratio is increased to decrease the average excitation of the exciter and alternator.

While I have shown and described particular embodiments of my invention it will be obvious to those skilled in the art that changes and modifications may be made without departing from my invention and I, therefore, aim in the appended claims to cover all such

changes and modifications as fall within the true spirit and scope of my invention.

What I claim as new and desire to secure by Letters Patent of the United States, is:—

5 1. In an electrical regulating system, a polyphase circuit, electromagnetic means connected to said circuit and electromagnetic means inductively coupled with said first mentioned electromagnetic means, for producing a voltage for regulating purposes which is equal to the sum of as many component voltages as there are phases of said circuit, each of said component voltages having a harmonic frequency of the fundamental frequency of said circuit.

10 2. In an electrical regulating system, a polyphase circuit, electromagnetic means connected to said circuit and electromagnetic means inductively coupled with said first mentioned means for producing a voltage for regulating purposes, said voltage having as many components as said circuit has phases and all of said components having a frequency which is equal to the harmonic frequency of the fundamental of said circuit which is in phase in said circuit.

15 3. In combination, a polyphase circuit, a regulator, and means interposed between said circuit and said regulator for energizing said regulator in accordance with the magnitude of a predetermined harmonic voltage of said circuit.

20 4. In combination, a polyphase circuit, an electrical regulator, including an operating element, and means connecting said circuit and said operating element, said means producing a voltage which is proportional to the sum of the in phase harmonic voltages of said circuit.

25 5. In combination, a polyphase circuit, an electrical regulator including a voltage responsive operating means and means connecting said circuit and said operating means, said connecting means applying a voltage to said operating means which is equal to the sum of a plurality of in phase harmonic voltages of the fundamental voltage of said circuit, each of said harmonic voltages being proportional in magnitude to the regulated electrical condition in a different one of the phases of said circuit.

30 6. In combination, a polyphase circuit, an electrical regulator including an electromagnetically operated main control means and electromagnetic inductive means connecting said circuit and said operating means, said connecting means applying to said main control means a voltage which is equal to the arithmetical sum of a plurality of voltages which are harmonics of the fundamental voltage of said circuit, each of said harmonic voltages being proportional to a different phase voltage of said circuit.

35 7. In combination, a three phase circuit, an electrical regulator including a main control

means, means connecting said main control means to said circuit, said connecting means producing a third harmonic voltage having three in phase components each of which is proportional to a different one of the phase voltages of said circuit.

8. In combination, a polyphase circuit, an electrical regulator including a main control element, a polyphase transformer having a mesh connected secondary winding, means connecting the primary winding of said transformer to said circuit and means connecting said main control element across the opening in said secondary winding.

9. In combination, a three phase circuit, an electrical regulator including a main control coil, a three phase transformer having an open delta connected secondary winding, means connecting the primary winding of said transformer to said circuit so that the phase voltages of said winding are responsive to variations in the regulated condition in their respective phases of said circuit, and means connecting said coil across the opening in said secondary winding.

10. In combination, a polyphase circuit, an electrical regulator including a main control element which is adapted to be responsive to variations in an electrical condition of said circuit, a polyphase iron core transformer having its secondary winding mesh connected, means connecting the primary winding of said transformer to said circuit so that the voltage across each phase winding is proportional to the magnitude of the regulated condition in a different phase of said circuit, said main control element being connected in series in the mesh-connected secondary winding, the magnetizing current of said transformer being high enough to saturate the iron core.

11. Means for producing a voltage for regulatory purposes of polyphase systems which varies in the proper manner for both balanced and unbalanced variations in the magnitude of the regulated condition and which also varies at a rate greater than the rate of variation of said regulated condition comprising a polyphase transformer having a no load magnetizing current sufficient to at least partially saturate its core and an open mesh connected secondary winding across which opening appears said regulatory voltage.

12. Means for producing a voltage for regulatory purposes which varies in proportion to variations in the arithmetical sum of the phase voltages of a three phase circuit but at a greater rate than said variations comprising a three phase transformer having a no lead magnetizing current sufficient to at least partially saturate its core and an open delta connected secondary winding, said voltage appearing across the opening in said delta.

13. In a regulating system, a polyphase cir-

cuit, a dynamo-electric machine connected thereto, a regulator for controlling said dynamo-electric machine, and means interposed between said regulator and said polyphase circuit for energizing said regulator in accordance with the magnitude of a predetermined harmonic voltage of said circuit.

14. In a regulating system, in combination, a polyphase dynamo electric machine, a polyphase circuit connected thereto, a regulator associated with said dynamo electric machine, means connecting said regulator to said circuit, said means including a polyphase transformer having an open mesh connected secondary winding.

15. In a regulating system, in combination, a polyphase dynamo electric machine, a polyphase circuit connected thereto, a regulator associated with said dynamo electric machine, means connecting said regulator to said circuit, said means including a polyphase transformer having its primary winding connected to be responsive to an electrical condition of said circuit, an open mesh connected secondary winding, and an iron core which becomes saturated during at least a portion of the cycle of its magnetizing current.

16. In a regulating system, in combination, a three phase alternator, a three phase circuit connected thereto, a voltage regulator associated with said alternator, said regulator including a main control means, means connecting said control means to said circuit including a three phase transformer having its primary winding connected across said line and its secondary winding open delta connected, said main control means being connected across said open delta.

17. In a regulating system, in combination, a three phase alternator, a three phase circuit connected thereto, a voltage regulator associated with said alternator, said regulator including a main control means, means connecting said main control means to said circuit including a three phase transformer having its primary winding connected to said circuit, its secondary winding delta connected with said main control means connected in said delta, and its magnetizing current sufficient to at least partially saturate its core.

18. In combination, a polyphase circuit, a translating device, and means for causing said translating device to respond to an electrical quantity whose frequency is different from the frequency of the fundamental of said circuit and whose magnitude varies in response to variations in a function of corresponding electrical conditions of a plurality of the phases of said circuit.

19. In combination, a polyphase circuit, means connected to said circuit, said means producing an electrical quantity consisting of a plurality of components, each of said components being proportional in magnitude respectively to an electrical condition of differ-

ent phases of said circuit, said components differing in frequency from the fundamental frequency of said circuit, and means connected to be responsive to said quantity.

20. In combination, a polyphase circuit, means connected to said circuit for producing an electrical quantity whose frequency is a multiple of the fundamental frequency of said circuit and whose magnitude is equal to the arithmetical sum of the magnitudes of a plurality of electrical quantities each of which is proportional respectively to corresponding electrical conditions of the phases of said circuit, and means responsive to said first mentioned electrical quantity.

In witness whereof, I have hereto set my hand this 15th day of April, 1930.

LAWRENCE H. JUNKEN.
